UNITED STATES PATENT OFFICE.

THOMAS H. COSTELLO, OF CHICAGO, ILLINOIS; ROSE M. COSTELLO AND WILLIAM E. COSTELLO, EXECUTORS OF SAID THOMAS H. COSTELLO, DECEASED, ASSIGNEES TO ROSE M. COSTELLO, TRUSTEE.

HINGE.

Application filed June 4, 1920. Serial No. 386,642.

My invention relates to movable stands in which a display panel is rotatively mounted by means of pivot hinges or trunnions between a plurality of suspending members. 5 The general structure which is the subject of my invention may be illustrated by that of a movable black-board in which the board on which the chalks are applied is suspended between two uprights and adapted to be rotated to change the inclination thereof or to display alternatively one or the other of the two faces.

When such devices are set for use, it is necessary that the pivotal connection shall 15 be adapted to be tightened so that the board or panel shall retain a rigid position relatively to the supports while in use or while work is being done thereon. This tension has usually been provided by screw threaded bolts, passing through the supports and taking into screw threaded members rigidly attached to the swinging frame, hand pieces being provided for tightening or loosening the bolts. The objectionable feature 20 of this construction consists in the fact that, when the ordinarily right-handed screw threaded pivots are tightened to give sufficient tension, a partial revolution of the panel to change the angular inclination 25 thereof or to display the other end to tighten, a condition which causes uncertain adjustment and frequently results in breaking the apparatus and tearing the panel from its supports.

It is one object of my invention to provide 30 simple, cheap, and efficient means for pivotally securing a display board or panel upon a supporting frame in such manner that it may be readily turned to any angle of inclination upon the pivot hinges, or rotated 35 to display either side as desired; it is a further object of my invention to provide pivot hinges or trunnions for the board or panel, which may be detachable from each other 40 whereby the board or panel may be connected or detached from the supports, and to provide a hinge or trunnion, the parts of 45 which may be adjusted in frictional or clamping engagement at any degree of tension and in which the parts are so positively held in such relation, that relative rotation in either direction will not vary the tension 50 at which they are set.

The principles of my invention are illus-

trated in the drawings in which Figure 1 is 55 a front elevation of a black-board of "knock-down" construction and including a swinging panel; Figure 2 is an enlarged detail elevation, partly in section, showing the interlocking connection between the crossbar and 60 one of the standards. Figure 3 is an elevation, partly in section, taken on the line 3-3 of Figure 2, the bracket being removed; Figure 4 is a sectional view showing one 65 form of my improved pivot hinge, and Figure 5 is a similar view, but showing another form thereof.

Like figures designate corresponding parts throughout the drawings.

Referring to the drawings, the black-board structure includes a black-board A and a pair of standards 5-5, the black-board including a frame having end members 6-6 normally arranged in parallelism with the standards. The black-board is 70 detachably connected to the upper ends of the standards by pivot hinges, each of which is 75 represented as a whole by the letter B.

Below the black-board the standards are 80 detachably connected by a cross-bar or chalk-rail 7, which acts as a brace therefor. This cross-bar 7 is fitted between the standards 5, and secured to the under face of this cross-bar and at each end thereof, is an angle bracket 8. Each bracket is provided 85 with one or more lugs 9, each lug including a head 9^a and a neck 9^b. Each standard is formed with one or more openings 10 in its inner face, the openings, of course, corresponding to the number of lugs 9. A counter-sunk plate 11 is suitably secured to the 90 inner face of each standard, and this plate is provided with one or more keyhole openings 12, the number, of course, corresponding to the number of lugs 9 on each bracket. 95 Each opening 12 includes a relatively large upper opening 12^a and a relatively small or restricted lower opening 12^b. The upper opening 12^a is of a size to receive the head 9^a of the corresponding lug, while the lower 100 or restricted opening 12^b is of a size to receive only the neck 9^b of said lug.

In assembling the cross-bar 7 and the standards 5-5, the heads 9^a of the lugs 9 of the brackets 8-8 are inserted through the 105 corresponding upper openings 12^a of the plates 11, and a downward pressure is exerted on the cross-bar. This downward

movement of the cross-bar will cause the necks 9^b of the lugs 9 to be moved into the lower or restricted openings 12^b of the plate 11.

5 In order to retain the cross-bar 7 against becoming accidentally disconnected pawls 13, 13 are respectively pivoted at their upper ends to the standards 5 by screws 14 so that they may be swung downwardly to engage the chalk-rail 7 and lock it in place.

10 Each of the hinges B includes a relatively stationary member 17 and a relatively movable member or head 18. The stationary member 17 is positioned against the inner 15 face of the standard 5 and is provided with upper and lower lugs 19, which fit into correspondingly sized recesses formed in the inner face of the standard, and not only prevent swinging movements of the member, 20 but also form a detachable and an interlocking connection between said stationary member and the standard. Centrally formed in the stationary member 17 is an angular opening 20. Formed on the outer face of the member 17 is an annular bearing rib 21 which surrounds the opening 20 and is spaced therefrom.

25 The relative movable member or head 18 is provided with a hollow boss 22 which extends towards the stationary member 17, and this boss is formed at its outer end with an annular seat 23 for receiving the annular bearing rib 21 of the stationary member 17. The end of the boss 22 is provided with an 30 opening 24 which is arranged concentrically to the annular seat 23. The diameter of this opening 24 is greater than the width in any direction of the angular opening 20 of the stationary member 17. The member 18 is 35 secured to the end member 6 of the black-board A by screws 25. The member 18 is furthermore provided with flanges 26 which engage the front and rear faces of the end member 6. These flanges relieve the attaching screws 25 of all strain when pressure is 40 exerted on the black-board or panel A. From the foregoing it will be observed that the relatively stationary and movable members 17 and 18 may be conjointly formed 45 with an annular bearing surface.

50 Referring to the construction shown in Figure 4, a clamping screw or bolt 27 is provided with a hand-wheel 28 having a shoulder 29 for engagement with a wear-plate 30 secured to the outer face of the standard 5. The clamping screw extends through an opening 31 formed in the standard 5 and carries at its inner end a flange 32 which is 55 arranged within the hollow boss 22 and has a diameter larger than the opening 24 of said boss. In this particular construction, the flange 32 is formed with an integral and angular shank 33 adapted to fit the opening 20 of the stationary member 17, so as to 60 prevent rotation of the flange 32. This com-

65 bined flange and shank is formed with a threaded bore for receiving the screw 27. The end of the shank 33 opposite the flange 32 may be provided with a flange 34 which 70 engages the outer face of the member 17 and prevents disengagement therefrom. It will thus be seen that the flanges 32 and 34 are 75 non-rotatable and serve to retain the hinge members 17 and 18 there-between. When the screw 27 is turned in the proper direction by the hand-wheel 28, to cause endwise movement of said screw, the non-rotatable flange 32 will be caused to engage the hollow boss and thereby cause the movable hinge member to be firmly clamped against the relatively stationary member, and thereby held 80 against turning movements in either direction.

85 A somewhat different construction is illustrated in Figure 5. A clamping screw or bolt 35 is provided at its inner end with an integral flange 36, and adjacent said flange the bolt is provided with an angular portion 37 which fits within the angular opening 20 and retains the flange 36 and also the 90 bolt from turning. Adjacent the angular portion 37, the bolt is formed with spaced ears 38—38 which engage the outer face of the stationary member 17. The ears 38 constitute a flange or a stop. As a result, the 95 relatively stationary member 17 and the relatively movable member 18 are retained between the flange 36 and the flange formed by the ears 38. A hand-wheel 39 is separate from the clamping bolt 35, but has threaded engagement with the outwardly projecting end thereof. This hand-wheel is also provided with a shoulder 40 which bears against the bearing or wear plate 30. It will thus 100 be seen that upon turning movement of the hand-wheel 39 in the proper direction, an endwise movement will be imparted to the clamping bolt 35, and the non-rotatable flange 36, which is carried thereby, will engage the hollow boss of the relatively movable member 18 so as to cause said hinge members 17 and 18 to be securely clamped 105 against turning movements in either direction.

110 From the foregoing it will be seen that the black-board A may be readily connected or disconnected from the standards by removing the bolt 27 of the construction shown in Figure 4, or by removing the hand-wheel 39 of the construction shown in Figure 5.

115 It will also be seen that when the black-board is adjusted at any predetermined angle, and the hinge members 17 and 18 securely clamped together, there will be no 120 tendency of either of the hinges B—B being loosened due to pressure being exerted on the black-board either above or below the horizontal plane containing the hinges.

125 It is manifest that the principles of my invention are of much broader application 130

than to black-boards alone. And they may be applied to other uses, as on mirrors, and the like, where a non-binding, adjustable, pivoted connection is desired.

5 I claim:—

1. In a hinge, a pair of facially contacting hinge members, one of which is stationary and the other rotatable relative thereto, there being registering openings in the hinge members, a securing bolt for the hinge members embodying a key portion non-rotatable and slidable through the stationary member and both rotatable and slidable through the rotatable hinge member for holding the latter against rotatable movement, and means formed integral with the bolt and cooperating with the outer side of the two hinged members to hold the hinged members and first named means in assembled formation.
2. In a hinge, a pair of facially contacting hinge members, one of which is stationary and the other rotatable relative thereto, there being registering openings in the hinge members, a securing bolt for the hinge members embodying a key portion non-rotatable and slidable through the stationary member and both rotatable and slidable through the rotatable hinge member, means on the bolt 30 engaging the outer face of the rotatable member to move the same into frictional binding engagement with the stationary member to hold the rotatable member against movement, and spring ears on the bolt engaging the exposed face of the stationary

member to cooperate with the last named means.

3. In a pivot hinge, the combination of relatively stationary and movable members conjointly formed with an annular bearing, 40 and a bolt extending concentrically through the bearing portions of said members and having a flange engageable with said movable member for clamping the latter to the stationary member upon endwise movement 45 of said bolt, said bolt being provided with a projecting ear for engaging the stationary member to retain said members in co-operative relation and between said ear and said flange.

4. In a hinge, a pair of facially contacting hinge members, one of which is stationary and the other rotatable relative thereto, the stationary member having an opening therein of polygonal formation and the rotatable member having a registering opening of a mean diameter greater than the extreme diameter of the opening in the stationary member, a bolt extending through the hinge members, a flange on one end of the bolt 60 for engagement with the outer face of the rotatable member and ears on the bolt spaced from the flange and positioned for engagement with the outer face of the stationary member to hold the two hinge members as- 65 sembed.

In witness whereof, I have hereto set my hand at Chicago, Illinois, this 29th day of May, 1920.

THOMAS H. COSTELLO.
